His Attorney

UNITED STATES PATENT OFFICE.

WILLIAM L. DAVIS, OF PETERSBURG, VIRGINIA.

DUST COVER.

Application filed June 28, 1923. Serial No. 648,376.

To all whom it may concern:

Be it known that I, WILLIAM L. DAVIS, a citizen of the United States, residing at Petersburg, in the county of Dinwiddie and 5 State of Virginia, have invented certain new and useful Improvements in Dust Covers; and I do hereby declare the following to be a full, clear, and exact description of the same, reference being had to the accompanying drawings, forming part of this 10 specification.

This invention relates to accessory devices for use with automobile engines for shielding the working parts from dust and grime.

15 The object of the present invention is to provide a dust cover for an automobile bloc of the overhead valve type which may be secured in place and which will shield the valve from dust, dirt, sand, and grime.

20 A further object of the present invention is the provision of a metal dust cover which may be secured on the engine bloc by attachment to the exhaust port without other connection with the engine. A still further 25 object is the provision of a dust cover in which provision is made for the oiling of the various joints.

Since automobile hoods are not at all tight fitting at the sides and are entirely open at 30 the front a great amount of dust and dirt blows over the working parts of the engine and soon builds up a deposit of appreciable size. This is unavoidable as it is absolutely 35 essential that air be drawn in from the outside to cool the motor. The present invention contemplates the provision of a metal casing covering the entire top of an engine bloc having overhead valves and covering the side of the bloc down to the lower chamber. The principal objection to a dust cap 40 of this nature is that it is awkward to remove and unless some means is provided for oiling the several joints through the casing or canopy of the dust cover it is almost as 45 easy to let the dust and dirt accumulate and to remove it from time to time as to be bothered with the constant removal of the cover.

The present invention contemplates the 50 provision of a shutter in the top of the hood and movable a slight amount so as to uncover all of the oil holes when desired and at other times to close the hood entirely. There is no absolute necessity for closing the 55 rear end of the dust cover since the draft is sufficiently strong to prevent the accumu-

lation of dust through the rear end, but I rather prefer to close the dust cover entirely since the rear flange aids materially in stiffening the entire body of the dust 60 cover.

In the drawings,—

Figure 1 is a perspective of my dust cover detached from the engine.

Fig. 2 is a vertical section through the 65 engine with the cover in place showing particularly the method of attachment.

Fig. 3 is a top plan view.

The invention is applicable for use with any one of the various better class engines 70 practically all of which use the overhead valves operated by rocker arms centrally pivoted on the engine bloc and the invention is shown in Fig. 2 in connection with such an engine. The cover includes a large vertical member 10 hereinafter called the side of the cover this being perforated as at 11 to match the opening in the exhaust port and at 12 to receive bolts which secure the exhaust manifold flange to the exhaust port 80 flange of the bloc. Near the bottom of the main member or side 10 there is a further small opening 15 to receive a rod which, in the Chevrolet motor illustrated, is part of the spark control mechanism. 85

The top 16 is rectangular and slightly greater in size than the engine bloc. This top member is preferably flat and has a great number of oil holes such as 17 preferably three times the number of valves, that is, 90 for a six cylinder engine there would be eighteen holes 17—one for oiling the central post of each valve, one for the long rod, and one for the connection between the valve stem and the rocker arms so that any and all places requiring oiling may be readily reached without removal of the cover. In addition to the holes 17 I provide optional holes 18 in case it is desired to secure the dust cover to the engine bloc by removing 100 one of the bolts from the rocker arm cap and by replacing such bolt with a stud 20 which should be of such length as to pass through the hole 18. When these studs are used a nut 21 should be provided to support the cover from beneath and the cover is then locked in place on the stud by means of a thumb nut 22 which serves as a lock nut. 105

The top 16 is preferably integral with the flange 25 parallel to the main side 10 and may also be integral with the front and rear top members 27 and 28 which in turn may or 110

2
may not be integral with the main front member 29 and the rear member 30. The front member of the dust cover 29 is generally in the form of a flange at right angles to the side 10 and conforms generally to the contour of the engine bloc having an extended portion 31 to fit the narrower portion of the engine casting.

As best seen in Fig. 1 the main rear flange 30 is of the same depth throughout and is a trifle shorter than the height of the side member 10. The member 30 may if desired be entirely omitted but the form shown is preferred in order to strengthen the device 15 as a whole and to enable the dust cover to be more snugly held against the engine.

The principle connection between the dust cover and the engine is obtained by the binding of the main portion or side 10 of the dust 20 cover between the exhaust port of the engine and the exhaust manifold and in general this will be the only connection of any kind between the engine and the cover although, as previously stated, the holes 18 25 may be provided and used as previously described.

In order to prevent dust from seeping through the holes 17 I provide a shutter 36 composed of a plurality of connected slats 30 or covers 37 operated as a unit by the handle 38 working in a slot 39 in the top member 16 of the dust cover. By shifting the handle 38 to one side the holes 17 are all uncovered and by moving the shutter to the other end 35 of the slot 39 all of the holes 17 are simultaneously closed making the dust cover substantially grit tight.

What I claim is:

40 1. The combination with an engine having overhead valves, of a cover enclosing said valves to shield same from dirt and grit and extending over the side of the engine bloc and secured thereto between the exhaust manifold and the exhaust port.

45 2. An automobile engine dust cover consisting of a side portion having an opening therein corresponding in size and shape to

the exhaust port and having a top member and front and back flanges forming together a cover for the sides and top of the engine, 50 said cover being secured on the engine bloc by the connections holding the exhaust manifold to the exhaust port.

3. The combination with an engine having overhead valves, a port in substantially the 55 vertical center line of the bloc, and a pipe communicating with said opening and detachably secured to the bloc, of a cover enclosing said valves to shield same from dirt and grit and extending over the side of 60 the engine bloc and secured thereto between said pipe and said bloc.

4. A dust cover for an automobile engine consisting of a rectangular side, a rectangular 65 top an L-shaped front and an L-shaped back, said cover being secured to the engine between the exhaust port and the exhaust manifold.

5. A dust cover for an automobile engine 70 consisting of a rectangular side, a rectangular top, an L-shaped front and an L-shaped back, said cover being secured to the engine between a detachable pipe and the body of 75 the engine bloc. said cover being held in place by the usual connections securing said pipe to said bloc.

6. A dust shield for an engine having overhead valves and side push rods consisting of means to shield the valves from dust and dirt, and a member having an opening 80 therein to align with the exhaust port opening, said member serving to protect the side rods from dust and dirt, and being secured to the engine bloc between the exhaust manifold and the exhaust port.

85 7. A dust shield for the side push rods of an engine consisting of a member having an opening therein to align with the exhaust port opening, said member serving to protect the side rods from dust and dirt, and being secured to the engine bloc between the 90 exhaust manifold and the exhaust port.

WILLIAM L. DAVIS.
